United States Patent

Des. 241,910
Patented Oct. 19, 1976

241,910

DOOR CLOSER COVER

Edward Herman Meisner, Wyckoff, N.J., assignor to
Eaton Corporation

Filed Oct. 29, 1974, Ser. No. 518,918

Term of patent 14 years

Int. Cl. D8—09

U.S. Cl. D8—203

FIG. 3

FIG. 4

FIG. 1

FIG. 2

FIG. 7

FIG. 8

FIG. 5

FIG. 6

FIG. 1 is a front view of a door closer cover showing my new design;

FIG. 2 is a top view of the door closer cover of FIG. 1;

FIG. 3 is a side view taken from the right side of FIG. 1;

FIG. 4 is a side view taken from the left side of FIG. 2;

FIG. 5 is a front view of a modification of the door closer cover showing a modification of the new design;

FIG. 6 is a top view of the door closer cover of FIG. 5 which is a mirror image of the bottom view;

FIG. 7 is a side view taken from the right side of FIG. 5; and

FIG. 8 is a side view taken from the left side of FIG. 6.

I claim:

The ornamental design for a door closer cover, substantially as shown and described.
